UNITED STATES PATENT OFFICE.

TOM DRAKE, OF ALTRINCHAM, ENGLAND, ASSIGNOR TO LINOTYPE AND MACHINERY LIMITED, OF LONDON, ENGLAND, A COMPANY.

ASSEMBLING MECHANISM OF TYPOGRAPHICAL COMPOSING MACHINES.

Application filed June 9, 1925, Serial No. 35,867, and in Great Britain June 13, 1924.

This invention relates to the assembling mechanism of typographical composing machines such as those known commercially under the trade mark "linotype" and kindred 5 machines of the kind which are provided with a plurality of superposed magazines from a plurality of which matrices can be assembled without involving the shifting of said magazines.

More particularly it releases to machines of the just-named kind in which a guideway for the matrices, adjustable into operative relationship with the front ends of different magazines, constitutes part of the assembling mechanism.

The adjustment of such guideways has heretofore been effected manually through, for example, a system of levers operated by a handle in the vicinity of the keyboard, 20 the work involved in the movement of the parts being thus imposed upon the operator.

The present invention contemplates an arrangement which relieves the operator of this work and enables the shift to be effected through the actuation of a key serving to control power-operated mechanism by which the guideway is adjusted.

The invention will now be described by reference to the accompanying drawings which are illustrative of a preferred constructional form and in which:—

Figure 1, is a front elevation of the pertinent parts of the mechanism, and

Figure 2, is an elevation of the same as viewed from the right-hand side of the machine.

In carrying out the invention in the manner here illustrated, there is employed a 40 mechanical relay, which is virtually a replica of that described for a different purpose in Letters Patent 1,105,157. That being so, it is not deemed necessary herein to describe anything beyond the salient 45 features of the said relay. To assist the reader in identifying the different parts of this relay with the corresponding parts described in the said patent, these parts are designated by the same reference numerals 50 in both cases, and to distinguish therefrom the elements of the particular arrangement according to the present invention from the said known parts, these elements are herein identified by reference letters.

55 The mechanical relay comprises a mutil-

lated gear wheel 107, which, when desired, is brought into mesh with a constantly rotated gear wheel 105 so as to be rotated thereby until the said mutilated gear wheel runs out of mesh. The bringing into mesh of the 60 two wheels 107, 105, is effected by means of a disc 109 rotated with the mutilated gear wheel 107, and carrying plungers 118 adapted by the actuation of a light-touch finger key A to be protruded into the path of an 65 arm 122 rotating with the constantly rotating gear wheel 105, and automatically moved out of that path during the partial rotation of the wheel 107, through a stationary cam 123.

In applying the aforesaid relay to the purposes of the present invention, the constantly rotated gear wheel 105 is secured to a shaft B which may be driven by sprockets C, D, and chain E, from the so-called intermediate 75 shaft F, and a cam 108 rotated with the mutilated gear wheel 107, is arranged to bear on the rear end of a lever G, which serves to adjust the guideways H. There are two diametrically opposite gaps in the mutilated 80 gear wheel 107, and two co-operating plungers 118, the protrusion of either of which latter, through the actuation of the key A as above mentioned, will result in the said 85 mutilated gear wheel 107 and the cam 108 being rotated through 180° and the consequent movement of the guideway-adjusting 90 lever G to one or other of its two terminal positions, thus, through intervening connections, controlling the position of the guideway H.

The form of the last mentioned connections may vary according to the construction of guideway with which the devices are to be employed. For the known form of 95 guideway H shown in the drawings, which heretofore, has been manually operated through a link I pivotally connected with lever arms J acting through links K on the guideway supports L, the lower end of this 100 same link I is guided as between rollers M, and through a roller N thereon, bears upon the front end of the adjusting lever G, under the weight of the pertinent parts assisted by a spring O which, in the construction illustrated, encircles the link I, these means serving to constantly maintain a roller G¹ on the rear end of the lever G, in contact with the periphery of the cam 108, or in engagement 105 with one or other of the two recesses 131, 110

132 in that cam, according to the position at the time occupied by the guideway H.

An adjustable brake P is preferably provided to prevent over-running of the mutilated gear wheel 107 when it runs out of mesh with the gear wheel 105; in the arrangement illustrated, this brake is in the form of a band partially encircling the disc 109, and capable of being slackened or tightened by a winged nut Q.

From the foregoing it will be seen that when an operative change of magazine is to be brought about by adjustment of the guideway H, all that the operator is called upon to do is to depress the light-touch key A which results in the projection of the respective plunger 118 into the path of the arm 122, which, through that plunger, turns the mutilated gear wheel 107 into mesh with the constantly rotated gear wheel 105. The cam 108 is thus turned through 180° and raises or lowers the front end of the lever G, which, through the before-described connections, correspondingly raises or lowers the guideway H. During this semi-rotation the cam 123 pushes the respective plunger 118 out of the path of the arms 122 so that when that portion of the rotation is completed and the respective mutilation of the wheel 107 is presented to the gear wheel 105, the said wheel 107 and cam 108 are stopped by the action of the brake P.

The arrangement as described above and illustrated in the drawings is designed to effect changes from one to another of two magazines, but it will be recognized that by suitably varying the number and position of the plungers 118, mutilated parts of the wheel 107 and the recesses 131, 132 of the cam 108, application of the invention to the alternative use of a larger number of magazines may be provided for.

Having described my invention, I declare that what I claim and desire to secure by Letters Patent is:—

1. In a typographical composing machine, the combination of a plurality of superposed inclined magazines, and assembling mechanism having a guideway adjustable alternatively into operative register with relatively different magazines, with a mechanical

relay comprising a mutilated gear rotatable on a fixed axis and a constantly rotating gear wheel with which the mutilated gear is capable of meshing for a partial rotation only at each cycle of operation, means operatively connecting the relay with the adjustable guideway and operative at each cycle of operation of the relay to move the guideway into one or another of its different operative positions, said means including a rocking lever actuated by the partial rotation of the mutilated gear, a vertically reciprocating rod operated by said lever, and a flexible connection between said rod and the guideway, together with a light-touch finger key mechanism controlling the operation of the relay.

2. In a typographical composing machine, the combination of a plurality of superposed inclined magazines, and assembling mechanism having a guideway adjustable alternatively into operative register with relatively different magazines, with a mechanical relay comprising a mutilated gear rotatable on a fixed axis and a constantly rotating gear wheel with which the mutilated gear is capable of meshing for a partial rotation only at each cycle of operation, a cam operatively fast to the mutilated gear wheel, a lever engaged by the cam and operatively connected to the adjustable guideway with the capacity for moving it into and out of operative register with one or another of the respective magazines at each cycle of operation of the cam, said connection including a vertically reciprocating spring-actuated rod operated by said lever, and a lever and link connection between said rod and the guideway, together with a light-touch finger key mechanism controlling the operation of the relay.

3. In a typographical composing machine the combination with mechanism according to claim 1, of a friction brake adapted to prevent over-running of the mutilated gear wheel when a mutilation thereof is presented to the constantly rotating gear wheel.

In testimony whereof I have affixed my signature hereto.

TOM DRAKE.
